CAN OPENER

Fred C. Dettman, Rochester, N. Y.

Application April 19, 1954, Serial No. 424,029

5 Claims. (Cl. 30—16)

1

This invention relates to can openers and more particularly to a can opener of the type adapted to shear a hole in the can top.

In can openers of the type described, it has often been the practice to employ the rim of the can as a bearing point for piercing the can top, particularly where an opening of considerable area is made. Such openings generally result in the cut away metal being bent against the inside side wall of the can, or result in a hole located away from the rim of the top, so that free flow from the can in pouring is prevented. When the rim of the can does not provide a sufficient shoulder, such devices as depend upon the rim as a bearing point are ineffective.

The present invention is directed to a can opener which utilizes the rim of the can solely as a guide for the can-top opening cutting operation, the cutting being done by a plunger having a stroke substantially parallel with the axis of the can, or the corresponding longitudinal dimension, where the can is other than circular. The present invention is further directed to the cutting of a broad U-shaped tongue, which is adapted to be bent inwardly toward the can center, the cut being made close to the rim whereby substantially unobstructed flow over the rim of the can may be had.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a front elevational view of the can opener, with parts broken away and shown in section;

Figure 2 is a sectional view of Figure 1 taken substantially on the line 2—2;

Figure 3 is a sectional view taken substantially on the line 3—3 of Figure 1;

Figure 4 is a sectional view taken substantially on the line 4—4 of Figure 1;

Figure 5 is a fragmentary view of a can showing the location and shape of the opening cut; and

Figure 6 is a fragmentary sectional view showing the manner in which the cut metal may be formed out of the way.

In Figures 1 and 2, there is shown a main support bar 10 having its upper end 12 formed at right angles to provide a guide, and its lower end 14 offset from the main body portion or upward extension 16 to provide a shoulder recess 18 adapted to engage the edge or rim of a can. Slid-

ably mounted on the bar 10 is a channel-sectioned cutter 20 having cutting edges 22, 24, and 26, arranged to provide a three-sided generally rectangular cut in the end 27 of a can 29. As shown in Figure 5, the cuts are indicated by the reference characters 30, 32 and 34, and the rectangular tongue cut thereby is indicated at 36. It will be noted that the cut 32 lies close to the rim of the can, and the tongue in being cut will be deflected inwardly and hinged along the line 37 toward the can center, where it will have the least tendency to obstruct the flow from the can. In practice, the cutting edge 24 could be arcuate, so that the cut 32 will lie on an arc somewhat concentric with the can rim, thereby cutting the can as close to the cylindrical side wall as possible, whereby substantially unobstructed flow from the can results. While the cutting edge 24 is shown as inclined, it will of course be understood that a transverse cutting edge may be employed, if desired.

The channel-sectioned member is provided with a yoke 38, having a central portion 40 bridging the flanges 42 and 44 of the channel member, side flank portions 46 and 48, and inwardly directed end flanges 47 and 49, adapted to slidably embrace the body portion 16 of the bar 10. The side flank portions are tied together by a transverse bar 50, which slides on the inside face of the bar 10, and acts to space the channel cutting member from the bar 10, sufficient to allow for the thickness of the can side wall and rim, and any seam between the side wall and the can end.

The central portion 40 of the yoke 38 is provided with an inwardly bent tongue 52, which forms with the channel member a socket for receiving the head end 54 of the plunger 56. The head end is slotted as at 58, and engages a centering ridge 60 formed on the tongue 52. The plunger extends through an aperture in the inwardly bent portion 62 of the channel member, the portion being an integral extension of the channel web 64. A compression spring 66, threaded on the plunger 56, bears against the head 54 and the inwardly bent portion 62. The plunger extends through an aperture in the upper end 12 of the bar 10, and is provided at its end with a threaded portion 67 adapted to receive a knob 68, and lock nut 70. Between the lock nut and the end 12, there is positioned on the plunger, a compression coil spring 72.

The plunger is adapted to slide the channel member with its cutting edge through a stroke, the length of which can be varied by changing the position of the knob, the lock nut being loosened to permit the change by threading the knob along the plunger end. In this manner, any desired stroke may be provided.

2

The plunger is readily assembled in place, with the knob, lock nut and coil spring 72 removed, by angularly projecting the threaded end 67 of the plunger, with the coil spring 66 threaded thereon, upwardly through the aperture in the end portion 62 of the channel member, and thence through the aperture in the end 12 of the bar 10, compressing spring 66 until the head clears the upper edge of the yoke 38, after which the plunger is swung into alignment within the channel member and the head allowed to seat within the pocket with its slot 58 engaging the tongue ridge 60, the spring 66 thereafter holding the plunger in place.

To assure that the can opener will firmly seat upon the edge of a can and be held in position during the cutting operation, a transverse member 73 secured to the bar 10, having angularly extending inwardly offset wings 74 and 76, is provided. The lower edges 73 and 80 of such wings are extended slightly and have relatively sharp edges 82 and 84, which engage the can top, inside the rim thereof, and prevent the can opener from slipping from cutting position.

The end portion 14 of the bar not only aids in holding the can opener properly positioned during the opening operation, but may be subsequently employed to pry the cut tongue 36 inwardly and under the can top, as shown in Figure 6, so as to be completely moved out of the opening, and to thereby prevent it from obstructing free flow from the can. Such end portion may be formed with a concave surface extending lengthwise thereof to embrace the cylindrical curvature of the can side wall, if desired.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. A can top opener comprising a support member having a portion adapted to lie along the cylindrical side of a can, an extension thereof offset inwardly adapted to extend above the can, said offset being adapted to bear upon the rim of a can, a channel-sectioned member slidably mounted on said extension with its open side facing away from said extension and having on its lower end a channel-shaped cutting edge, and means for guiding the sliding movement of said channel-sectioned member whereby to cut a channel-shaped tongue from the top of the can immediately inside the rim thereof, when the cutting edge is moved downwardly below the shoulder.

2. A can top opener comprising a support member having a portion adapted to lie along the cylindrical side of a can, an extension thereof offset inwardly adapted to extend above the can and having an inbent upper end, said offset forming a shoulder adapted to bear upon the rim of a can, a channel-sectioned member slidably mounted on said extension with its open side facing away from said extension and having on its lower end a channel-shaped cutting edge, means for guiding the sliding movement of said channel-sectioned member upon the extension, an operating guide rod nested in the channel and adapted to move therewith, said rod extending upwardly through an aperture in said inbent end, 75

a knob on the upper end of said rod, and a return spring threaded on said rod between said knob and inbent end.

3. A can top opener comprising a support member having a portion adapted to lie along the cylindrical side of a can, an extension thereof offset inwardly adapted to extend above the can and having an inbent upper end, said offset forming a shoulder adapted to bear upon the rim of a can, a channel-sectioned member slidably mounted on said extension with its open side facing away from said extension and having on its lower end a channel-shaped cutting edge, means for guiding the sliding movement of said channel-sectioned member upon the extension, an operating guide rod nested in the channel and adapted to move therewith, said rod extending upwardly through an aperture in said inbent end, a knob and lock nut threaded on said upper end to vary the stroke of said channel member, and a coil spring on said rod between said nut and inbent end.

4. A can top opener comprising a support member having a portion adapted to lie along the cylindrical side of a can, an extension thereof offset inwardly adapted to extend above the can and having an inbent upper end, said offset forming a shoulder adapted to bear upon the rim of a can, a channel-sectioned member slidably mounted on said extension with its open side facing away from said extension and having on its lower end a channel-shaped cutting edge, means including a yoke embracing and secured to said channel member having guide fingers embracing said extension, said yoke having means forming a pocket within said channel member, for guiding the sliding movement of said channel-sectioned member, said channel member having an inbent portion at its upper end, an actuating rod extending through apertures in said extension inbent end and said inbent portion, and having its lower portion nested in said channel and having a head on its lower end seated in said pocket, and a coil spring threaded in said lower portion and bearing on said head and against said inbent portion.

5. A can top opener comprising a support member having a portion adapted to lie along the cylindrical side of a can, an extension thereof offset inwardly adapted to extend above the can and having an inbent upper end, said offset forming a shoulder adapted to bear upon the rim of a can, a channel-sectioned member slidably mounted on said extension with its open side facing away from said extension and having on its lower end a channel-shaped cutting edge, means including a yoke embracing and secured to said channel member having guide fingers embracing said extension, said yoke having means forming a pocket within said channel member, for guiding the sliding movement of said channel-sectioned member, said channel member having an inbent portion at its upper end, an actuating rod extending through apertures in said extension inbent end and said inbent portion, and having its lower portion nested in said channel and having a head on its lower end seated in said pocket, a coil spring threaded in said lower portion and bearing on said head and against said inbent portion, a knob on the upper end of said rod, and a return spring disposed upon said rod between said knob and inbent end.
